DRAFTING ASSEMBLY OR KIT

Ellwood H. May, Rockford, Ill., assignor to Engineering Manufacturing Co., Sheboygan, Wis., a corporation of Wisconsin

Application February 9, 1948, Serial No. 7,150

3 Claims. (Cl. 33—80)

1
This invention relates to a drafting assembly or kit comprising a drafting board and an associated T square mounted thereon.

An object of the invention is to provide an assembly of the above character with novel means for retaining the drafting board and the T square in an assembled relation so as to prevent accidental loss of the T square while at the same time permitting the T square to slide relative to the board as required by a user.

Another object of the invention is the provision in an assembly of the above character having novel clamping means acting between the head of the T square and the board for frictionally securing the T square in a desired adjusted position on the board.

Another object of the invention is to provide an assembly of the above character which is simple in construction and which is relatively inexpensive to manufacture.

Another object of the invention is to provide a drafting board and T square assembly of the above character which can be made in relatively small sizes for students and the like so that it is readily portable, which is always ready for use, and in which the board and T square are held together as a unit so that it can be carried between classrooms or the like and the user does not have to worry about the straight edge becoming displaced from the board.

Other objects and advantages of the invention will become apparent from the following detailed description taken in connection with the accompanying drawings, in which—

Figure 1 is a bottom plan view of a drafting board and T square assembly embodying the invention, and

Fig. 2 is a side elevational view of the above assembly.

Referring now to the drawings, the invention is shown embodied in a portable drafting board and T square assembly or unit. In general, the latter comprises a drafting board 10 with a T square 11 having a straight edge blade 12, extending across a front 13 of the board 10 and movable relative to the board as required by the user. At one end the blade 12 is attached to a head 14 slidably engaging a side edge 16 of the board and arranged to frictionally engage the board to maintain the blade 12 in any desired position on the front of the board.

As shown in Figure 1 the drafting board 10 is rectangular in shape and comprises spaced substantially straight parallel side edges 16 and 17 and a top edge 18 and a bottom edge 19. The

board may be formed from any suitable material. For purposes of illustration the board is shown in this instance as being formed from wood. The front 13 of the board is preferably formed with a smooth surface for the reception of drawing paper or the like.

Provision is made for securing the T square 11 in an assembled relation with the board 10 in a manner which prevents accidental removal of the

5 **10** T square from the board yet permits free movement of the blade 12 between the top edge 18 and the bottom edge 19 of the board. For this purpose suitable clips 20 and 21 associated with opposite ends of the T square 11 and engageable with a back 15 (see Fig. 2) of the board 10 are utilized. As shown in Fig. 2 the clip 20, connected to the end of the straight edge 12 away from the head 14, comprises a U-shaped member having spaced legs 22 and 23 connected together by a bridging member 24. The leg 22 is rigidly secured to the side of the blade away from engagement with the paper receiving surface 13 as by a rivet 26 and the leg 23 is shaped to be received in a rabbet 27, the purpose of which will presently 15 appear, formed along the side edge 17 of the board and opening on to the side edge 17 and back 15 respectively. The bridging portion 24 spaces the portions 22 and 23 apart a distance corresponding to the combined thickness of the blade 12 and the thickness of the board 10 at its side edge 17. Preferably the legs 22 and 23 are spaced so that there is a small clearance between the clip 20 and the edge of the board.

20 The clip 21 as contemplated in this embodiment of the invention is formed by a plate 25 secured to the side of the head 14 away from the blade 12 and shaped to be received in a rabbet 28, formed along the side edge 16 of the board 10 and opening on to the side edge 16 and back 15 respectively. The thickness of the head 14 is substantially equal to the thickness of the board measured along the side edge 16 so that the plate 25 flush with the back of the head is readily receivable in the rabbet.

25 **40** An important feature of this drafting board and T square assembly is the provision wherein the T square may be readily clamped in any desired position so that the blade 12 on the front 13 of the board 10 can be located as required with respect to the drawing paper. In this embodiment of the invention this is effected by a movable clamp 29 mounted on the head 14 of the T square 11 and shaped to be engageable with a shoulder 31 spaced from the side edge 16 of the board 10 against which the head 14 abuts and a spring 32

disposed between the movable clamp 29 and the head 14 urging the head into engagement with the side edge 16 and the clamp into engagement with the shoulder 31. The movable clamp 29 as shown in Figures 1 and 2 is formed in part by the plate 25 which is mounted on the head 14 for relative movement and an upstanding flange 32 integral with the plate 25 and shaped to abut the shoulder 31. As best shown in Fig. 2 the shoulder 31 is formed by one side of a groove 33 formed inwardly from the side edge 16 on the back 15 of the board 10 and intersecting the rabbet 28. To permit relative movement of the clamp 29 with respect to the head 14, the plate 25 is formed with spaced elongated slots 34 through which screws 36 extend for loosely retaining the plate 25 in position on the head 14. Washers 37 may be disposed between the head 14 and the plate 25 to minimize friction between the respective parts.

While the spring 32 may take many different shapes and many suitable means may be employed for mounting the spring, as shown herein, the spring 32 comprises a U-shaped member disposed between the plate 25 and the head 14 to effect a clamping action of the flange 32 against the shoulder 31 and the head 14 against the side edge 16. Thus, one end 38 of the spring is anchored under a tab 39 formed from the plate 25 and the other end 41 of the spring is received in an opening 42 in a post 43 rigid with the head 14. The post 43 projects through an elongated slot 44 formed in the plate 25 and disposed between the spaced slots 34.

As shown in this embodiment of the invention, the back 15 of the board 10 is formed with rabbets 27 and 28 adjacent the side edges 16 and 17 respectively. This construction permits a central portion 46 of the board 10 as seen in Fig. 2 to rest on the flat surface and the lower portions of the clips 20 and 21 are raised sufficiently from the flat surface to permit free movement of the T square 11 on the board 10.

Means for limiting the movement of the T square 11 relative to the top edge 18 and bottom edge 19 of the board 10 is provided for preventing the accidental removal of the T square 11 from the board 10. As shown in Figure 1 stops in the form of pins 47 are positioned at each end of the rabbets 27 and 28 respectively. Thus, when the blade 12 is moved to the top edge 18 of the board the clips 20 and 21 engage the respective pins 47 and prevent removal of the T square 11 from the drafting board 10. In a similar manner the stops 47 at the bottom edge 19 of the board also prevent removal of the blade 12 when the latter is moved to the bottom of the drafting board.

I claim:

1. In a portable drafting board and T square assembly, the combination of: a drafting board having first and second side edges in spaced substantially parallel relation, the opposed faces of the board being plane and forming a front working surface and a plane back, said board having a rabbet of substantial depth along the first side edge opening on to the back and first side edge of the board, said rabbet including a cut of greater depth than the balance of the rabbet located to form a shoulder spaced inwardly from and parallel to the first side edge of the board, a T square comprising a head portion of substantially lesser thickness than the board having an edge shaped to abut against the first side edge of said board, and a straight edge extending across and in contact with the front surface of the board having

one end rigidly attached to said head and the opposite end extending to the second side edge of the board, a plate attached to the back of the head comprising a first portion shaped to extend into said rabbet from the first edge of the board and a second portion in side by side relation with the back of said head and having an elongated slot, means engageable with said second portion and extending through said slot for retaining said plate in an assembled relation with said head, a flange integral with said plate and engageable with said shoulder, and a compression spring acting between said plate and said head for releasably urging the edge of the head into clamping engagement with the first edge of the board and said flange into clamping engagement with the shoulder, said plate, said means, said flange and said spring being shaped and positioned wholly between planes defined by the front and back surfaces of said board.

2. In a portable drafting board and T square assembly, the combination of, a drafting board having first and second side edges in spaced substantially parallel relation, the opposed faces of the board being plane and forming a front working surface and a plane back, said board being provided with rabbets of substantial depth along the first and second side edges opening on to the back and side edges of the board, said rabbet along the first side edge including a cut of greater depth than the balance of the rabbet located to form a shoulder spaced inwardly from and parallel to the first side edge of the board, a T square comprising a head portion of substantially lesser thickness than the board having an edge shaped to abut against the first side edge of said board, and a straight edge extending across the front surface of the board having one end rigidly attached to said head and the opposite end extending to the second side edge of the board, a clip comprising spaced legs, means for securing one of said legs rigidly to said opposite end of said straight edge against the front side thereof, the other legs extending into the rabbet along the second side edge from the edge of the board forwardly of the plane defined by the back of the board, a plate attached to the back of the head with respect thereto, said plate having a portion shaped to extend into said first rabbet from the first edge of the board and a second portion in side by side closely spaced relation with the back of said head, said second portion having a plurality of spaced slots, spaced headed members extending through two of said slots for supporting said plate on said head for movement with respect thereto, a post rigid with said head and extending through a slot disposed between said headed members, a flange integral with said plate engageable with said shoulder, and a compression spring disposed between said post and said plate for releasably urging the head into engagement with the first edge of the board and said flange into engagement with the shoulder, said plate, said headed members, said post, said flange and said spring being shaped and positioned wholly between planes defined by the front and back surfaces of said board.

3. In a portable drafting board and T square assembly, the combination of, a drafting board having first and second side edges in spaced substantially parallel relation, the opposed faces of the board being plane and forming a front working surface and a plane back, said board being provided with rabbets of substantial depth along the first and second side edges opening on to

the back and side edges of the board, said rabbet along the first side edge including a cut of greater depth than the balance of the rabbet located to form a shoulder spaced inwardly from and parallel to the first side edge of the board, a T square comprising a head portion of substantially lesser thickness than the board having an edge shaped to abut against the first side edge of said board, and a straight edge extending across the front surface of the board having one end rigidly attached to said head and the opposite end extending to the second side edge of the board, a clip comprising spaced legs, means for securing one of said legs rigidly to said opposite end of said straight edge against the front side thereof, the other legs extending into the rabbet along the second side edge from the edge of the board forwardly of the plane defined by the back of the board, a plate attached to the back of the head with respect thereto, said plate having a portion shaped to extend into said first rabbet from the first edge of the board and a second portion in side by side closely spaced relation with the back of said head, said second portion having a plurality of spaced slots, spaced headed members extending through two of said slots for supporting said plate on said head for movement with respect thereto, a post rigid with said head and extending through a slot disposed between said headed members, a flange integral with said plate engageable with said shoulder,

stops disposed in said rabbets adjacent each corner of the board positioned to be engaged by said clip and said plate to thereby prevent removal of the T square from the board, and a compression spring disposed between said post and said plate for releasably urging the head into engagement with the first edge of the board and said flange into engagement with the shoulder, said stops, said plate, said headed members, said post, said flange and said spring being shaped and positioned wholly between the planes defined by the front and back surfaces of said board.
